UNITED STATES PATENT OFFICE

166,143

TOOTHBRUSH, TOOTHPASTE, AND EYE- GLASS POCKET BRACKET

Myron A. Block, Shorwood, Wis.

Application September 7, 1951, Serial No. 16,575

Term of patent 14 years

(Cl. D4—3)

To all whom it may concern:

Be it known that I, Myron A. Block, a citizen of the United States, residing at Shorwood, in the county of Milwaukee and State of Wisconsin, have invented a new, original, and ornamental Design for a Toothbrush, Toothpaste, and Eye-glass Pocket Bracket, of which the following is a specificaion, reference being made to the accompanying drawing, forming part thereof.

Figure 1 is a front view in perspective, illustrating the toothbrush, toothpaste, and eyeglass pocket bracket showing my new design.

Figure 2 is an end elevational view of the bracket.

Figure 3 is a vertical section taken on a line through the center of the bracket.

I claim:

The ornamental design for a toothbrush, toothpaste, and eyeglass pocket bracket, as shown.

MYRON A. BLOCK.
